REFRIGERATOR CABINET

Albert P. Ball, Detroit, Mich., assignor to Briggs Manufacturing Company, Detroit, Mich., a corporation of Michigan

Application January 2, 1934, Serial No. 704,870

2 Claims. (Cl. 312—189)

This invention relates to refrigerator cabinets and more particularly to cabinets useful in iceless refrigerating systems. An object of the invention is to provide an improved refrigerator cabinet having a main or inner storage compartment and a supplementary or outer compartment formed by means of a casing hinged therein and accessible when the main cabinet door is open, said casing being mounted to swing 5 through the door opening to permit access to the main compartment.

A further object of the invention is to provide a refrigerator cabinet of the foregoing type having improved means for maintaining the temperature and air within the supplementary compartment in desirable condition for the storage of certain foods, permitting the segregation of foods with high water content and preventing contamination of foods stored in the main or inner 10 compartment.

This invention relates to refrigerator cabinets of the type disclosed in my co-pending application Serial 692,560, filed October 7, 1933, and the present application is a continuation in part 15 thereof.

Other objects of this invention will appear in the following description and appended claims, reference being had to the accompanying drawings forming a part of this specification where- 20 in like reference characters designate corresponding parts in the several views.

Fig. 1 is a front elevation partly broken away 25 illustrating a refrigerator cabinet embodying the invention.

Fig. 2 is a fragmentary horizontal section taken substantially along the line 2—2 of Fig. 1 in the direction of the arrows.

Fig. 3 is a detail section taken on the line 3—3 30 of Fig. 2 in the direction of the arrows.

Fig. 4 is a detail section taken on the line 4—4 35 of Fig. 3 in the direction of the arrows.

Fig. 5 is a fragmentary vertical section taken substantially on the line 5—5 of Fig. 1 in the direction of the arrows.

Fig. 6 is a fragmentary vertical section taken substantially on the line 6—6 of Fig. 1 in the direction of the arrows.

Fig. 7 is a fragmentary horizontal section taken substantially on the line 7—7 of Fig. 1.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of 55 description and not of limitation, and it is not

intended to limit the invention claimed herein beyond the requirements of the prior art.

Referring to the drawings wherein several preferred adaptations of the invention are illustrated by way of example, there is shown at 10 a suitable refrigerator cabinet having enclosing walls which may be of composition formation composed of insulating material and an outer and an inner metal sheathing. The front of the cabinet has the usual door opening controlled by a door 11 (shown in dotted lines in Fig. 2) hinged at 12 to the front wall of the cabinet. The door may also be a conventional construction including insulating material sheathed between outer and inner panels.

In accordance with the present invention there is mounted within the main compartment of the cabinet a casing member generally indicated at 13 which forms a supplementary compartment extending vertically within the compartment ad-

jacent the door opening. The casing 13 may be formed from sheet metal and comprises a vertical back wall 14, forwardly extending sides 15 and forwardly extending top and bottom walls 16 and 17 respectively. A box-like casing is thus 25 provided which has an open face at its front fac-

ing the main cabinet door 11. The bottom portion of the member 13 is provided with a panel member 18 which has a flanged opening 19 in the face thereof forming a partially closed compart- 30

ment bounded by the back wall 14, the sides 15, the forwardly extending bottom wall 17, and a top member 20 (Fig. 6). The casing member is preferably hinged within the cabinet to the top 35 and bottom walls thereof at points rearwardly of the jamb faces of the door opening, see Fig. 5.

In the present instance there is fixed to the bottom wall 17 of the casing 13, adjacent the hinged edge of the door 11, a depending pivot pin 21 40 which is adapted to seat in a recess or socket 22 provided in the base of the main cabinet, the pin 21 being rotatable within the socket or recess.

Vertically aligned with the pivot pin 21 is a retractable pivot pin 23 carried by the top wall 16 of the casing 13. A recess or socket 24 is pro- 45

vided in the top portion of the main cabinet and the pin 23 is rotatable within such socket or recess. The pivot pin 23 extends inside a casing 25. A headed portion 26 is secured to a rod 27 which joins the pivot 23 and the head 26. Within the 50

casing 25 and surrounding the rod 27 is a compression spring 28 which acts to maintain the pivot pin 23 in the position shown in Fig. 5 at all times except when the spring is compressed by retraction of the pivot pin 23 within the chamber 55 25. An opening 29 is provided in the top 16 of the casing 13 and is of sufficient size to permit the casing 25 to extend upwardly therethrough. At its upper end the casing 25 is screw threaded as at 25a and lock nuts 30 and 31 are screw threaded 60

thereon on opposite sides of the member 16 and cooperate with the screw-threaded portion 25a of the casing 25 to maintain the pivot 23 in the position as here shown. When it is desired to remove the casing 13 from the main compartment 5 the head 26 may be grasped and pulled in a downward direction to retract the pivot 23 from the socket or recess 24 and the whole compartment may be lifted in such a manner that the pivot 21 is removed from the recess or socket 22. When in position within the compartment the pivots 21 and 23 will be held within their respective sockets under sufficient spring pressure to prevent chattering or rattling of the casing 13 during operation of the refrigerator mechanism.

It will be seen that the casing 13 is pivoted adjacent one side of the door opening preferably at the same side of the cabinet as the hinge 12 for the main door 11 so as to swing outwardly through the door opening when the door 11 is open. The casing, therefore, provides a supplementary door adapted to swing outwardly in the same direction as the main door so as to provide 25 access to the interior of the cabinet. Means are preferably provided for locking the casing or supplementary door 13 in its inner closed position and for limiting its inward swinging movement so that it may be held in proper position with 30 relation to the outer door when the latter is closed. In the present instance the compartment door or casing 13 is yieldingly held in closed position by means of a spring 40 having one end secured to the side 15 of the member 13 and having 35 its other end formed with a latch portion 41 which is adapted to engage with a latch member 42 secured to the cabinet wall. The latch member 42 is provided with a wedge-shaped abutment or keeper portion 43 which is engaged by the 40 latch portion 41 of the spring 40. When the compartment door 13 is swung into closed position, as shown in Fig. 2, the spring 40 will be compressed as the latch portion 41 moves into locking engagement with the abutment 43. By the 45 provision of a plurality of locking members adapted to engage the compartment 13 at different points in its height the compartment 13 will be yieldingly locked in position when closed so as to prevent vibration thereof.

50 As illustrated in Figs. 2 and 5 the casing or compartment member 13 cooperates with the cabinet walls so as to effect a seal partly or wholly around the marginal edges of the main door opening. In this form of the invention the forward marginal edges of the casing 13, preferably 55 along the sides, top and bottom thereof, are provided with a sealing strip 50 which may be formed of rubber or other suitable yieldable material. This strip extends outwardly from the marginal edges of the compartment 13 and may extend 60 continuously or nearly continuously, as desired, around such edge of the casing and is so positioned as to contact with a flange 51 formed adjacent the rear marginal edge of the jamb face 65 52. The flange or abutment 51 may be omitted at the vertical side adjacent the pivots 21 and 23 and at this side the sealing will be effected by engagement of the compressible strip 50 with the straight tapered jamb face 52. Thus it will 70 be seen in Figs. 2 and 5 that the sealing strip 50 effects a seal of the door opening around its inner edges, thereby providing a sealing means supplementary to the sealing means provided for sealing the door 11.

75 Referring to Figs. 1 and 2 it will be noted that

the casing 13 also functions as a closure means for the front opening of the evaporator casing. There is illustrated at 60 any conventional type of evaporator casing or housing which may include inner and outer walls 61 and 62 spaced for the reception of coiled piping or other conduits (not shown) through which the refrigerant flows. The evaporator 60 provides the usual sharp freezing compartment 63 within which are located ice trays 64. The front of the evaporator casing is 10 open to permit removal of the ice trays and in the present instance this opening is controlled by means of the rear wall 14 of the casing 13 so that when the casing or compartment 13 is swung into closed position within the main refrigerator 15 compartment it will seal the front opening of the evaporator casing. In the present instance the front marginal wall of the evaporator casing is formed with a continuous groove or channel 65 within which is anchored the beaded edge 66 of 20 a sealing strip 67 composed of rubber or other suitable material. The strip 67 forms a projecting flexible lip in position to be engaged by the back wall 14 of the casing 13, and since the sealing strip extends around the marginal edges 25 of the front opening of the evaporator casing 60 the ice tray compartment thereof will be sealed when the casing 13 is in its closed position.

The interior of the supplementary compartment or casing 13 is provided with suitable shelving so that articles of food may be conveniently placed thereon. In the present example a series 30 of shelves 70 of the wire formed basket type are mounted within the casing. Each shelf is suitably formed of longitudinally extending strands 35 71 and cross strands 72 extending substantially at right angles to the strands 71 and secured to the latter at points intermediate the length thereof. The strands 71 and cross strands 72 are formed to provide a shelf having a bottom portion and an upwardly extending side portion. The side members 15 of the compartment 13 are punched in such a manner that shelf supporting lugs 73 and 73a are formed which extend inside 40 the compartment 13 a suitable distance to engage 45 and support the members forming the shelves 70. As shown in Fig. 3 a series of lugs 73 are provided in the sides 15, the shelf engaging portions of the lugs extending substantially at right angles to each other. Such a construction maintains the 50 shelves securely in place within the compartment 13 and permits a removal of the shelves only if tilted in an upward direction a sufficient distance to clear the top of the lugs 73 adjacent the forward edge of the shelf, after which the shelf 55 may be moved horizontally from the compartment, which movement will disengage the shelf from the lugs 73a extending substantially at right angles to the lugs 73. The arrangement of the lugs 73 and 73a relative to the shelf 70 is such 60 that the weight of the shelf and its contents acts to maintain the shelf firmly wedged in position between the walls of the compartment 13.

By this construction it will be observed that 65 ventilating openings are provided along the vertical sides 15 of the compartment 13. These openings are of such size and of such a number as to permit a desirable exchange of air between the compartments so as to prevent sweating but are not of such a size as to permit a substantial 70 amount of circulation of the refrigerated air from the main compartment through the supplementary compartment. A compartment is thus provided in which a somewhat higher temperature 75 than the main compartment, such as at a

differential of approximately 10° F., may be maintained and the compartment is therefore particularly adapted for the storage of foods such as fruits and vegetables which should not be chilled to the temperatures ordinarily maintained in the cabinet. The supplementary compartment also is particularly advantageous for the storing of foods which cannot be stored when subjected to such a circulation of refrigerated air as to cause dehydration of the foods.

It will be noted that the sealing strip 67 will not only effect a relatively tight closure of the front of the evaporator or ice tray housing, but will also act as a cushioning means and yielding stops effective to exert sufficient pressure against the back wall 14 of the casing 13 so as to prevent objectionable noises due to vibration or chattering.

The lower portion of the door compartment 13 is enclosed at the front by the plate 18 and the interior of the compartment is accessible through the flanged opening 19. It has been found that such a compartment is particularly desirable for the storage of tall articles such as milk bottles and the like and the member 18 prevents displacement of articles contained in the lower compartment.

In order to permit cleaning of this compartment a slidable door 18a is provided at a point directly beneath the flanged opening 19, the member 18 having spaced vertical edges folded to form channels 18b to engage the vertical side edges of the door 18a. The door 18a thus may be removed or installed by sliding it vertically in the channels 18b.

In the embodiment of my invention here shown the outer panel 80 of the cabinet 10 extends to a point adjacent the jamb face 52 and is flanged as at 80a to provide a channel or rabbeted portion 40 which extends around the margin of the door opening. The inner panel 81 is provided with the flange or abutment 51 and extends outwardly and integrally therefrom to form the entire jamb face 52, thus providing an integral breaker strip for 45 the door opening. The panel 81 terminates in a bent flanged portion 81a overlapping the portion 80a of the outer panel 80. A sealing strip 82 of rubber or other suitable material is interposed and clamped between the overlapping flanges of 50 the outer panel 80 and the inner panel 81 and extends outwardly therefrom to form a sealing strip which is contacted by the door 11 when in the closed position as shown in Fig. 2.

As shown in Fig. 5 the door 11 may be constructed of an outer panel 11a and a separate inner panel 11b. The ends of the outer panel 11a and the inner panel 11b terminate at points spaced apart from each other and the gap between the ends of the panels is closed by a removable breaker strip 11c which is secured to the frame portion 11d of the door. The space between the outer panel 11a and the inner panel 11b is filled with any suitable insulating material.

From the foregoing it will be seen that a construction has been provided which permits the supplementary compartment 13 to be located wholly within the refrigerated space of the main compartment in the rear of the breaker strip or jamb face of the door opening, and a cabinet construction has been provided in which the inner panel 81 is formed to provide the jamb face of the door opening and cooperates with an edge of the outer panel 80 to maintain the sealing strip

82 in position for contacting with the rabbeted portion of the door 11 when the door is in the closed position.

I claim:

1. A domestic refrigerator comprising a cabinet having a main door opening, an inner metal panel forming an inner main compartment and a door jamb located within said opening, the inner panel at the juncture of said main compartment and said door jamb having an inwardly extending integral abutment extending around a plurality of sides of said main door opening, said inner panel terminating in an angular flange extending around said door jamb, an outer metal panel forming the exterior wall of said cabinet and having a flange cooperating with said inner panel flange within the door opening, a movable outer door of a size to close said opening, an auxiliary food compartment associated with said door in rear thereof and including a casing having a rear vertical wall and enclosing forwardly extending side walls provided with an angularly disposed surrounding flange adapted to effect an approximate closure of said opening and to expose said food compartment when the outer door is opened, said casing being movable horizontally through said opening independently of the door, a sealing strip carried by said surrounding casing flange and engaging the door jamb portion and abutment of the inner metal panel to seal the inner main compartment when the casing is in closed position, and a sealing strip carried by the flange on the inner metal panel and engaging the outer panel flange, said last named sealing strip having a portion engaged by said outer door when in closed position to seal the auxiliary food compartment and to provide an additional seal for the main compartment.

2. A domestic refrigerator comprising a cabinet having a main door opening, an inner metal panel forming an inner main compartment and a door jamb located within said opening, the inner panel at the juncture of said inner main compartment and said door jamb having an inwardly extending abutment at a plurality of sides of said main door opening, said inner panel terminating in an angular flange extending around said door jamb, an outer metal panel forming the exterior wall of said cabinet and having a flange cooperating with said inner panel flange within the door opening, a movable outer door of a size to close said opening, an auxiliary food compartment associated with said door in rear thereof and including a casing having a rear vertical wall and enclosing forwardly extending side walls provided with an angularly disposed surrounding flange adapted to effect an approximate closure of said opening and to expose said food compartment when the outer door is opened, said casing being movable horizontally through said opening independently of the door, a sealing strip carried by said surrounding casing flange and engaging the door jamb portion and integral abutment of the inner metal panel to seal the inner main compartment when the casing is in closed position, and a sealing strip associated with and interposed between the cooperating flanges on the inner and outer metal panels and having a portion adapted to be engaged by said outer door when in closed position for sealing the auxiliary food compartment.

ALBERT P. BALL.
